Primary Examiner — Darlington Ly

Attention is directed to the decision of Golden eye Media USA, Inc. v. Trolley Bags UK Ltd, 3:18-cv-02109 (S.D. Cal.) relating to this patent. This reexamination may not have resolved all questions raised by this decision. See 37 CFR 1.552(c) for ex parte reexamination and 37 CFR 1.906(c) for inter partes reexamination.

EX PARTE
REEXAMINATION CERTIFICATE

THE PATENT IS HEREBY AMENDED AS 5
INDICATED BELOW.

AS A RESULT OF REEXAMINATION, IT HAS BEEN DETERMINED THAT:

The claim 1 is cancelled. 10
